UNITED STATES PATENT OFFICE.

MYRON E. KENNEY, OF EVERETT, WASHINGTON.

CONDENSED-MILK-CAN PERFORATOR.

Application filed March 17, 1926. Serial No. 95,328.

This invention relates to new and useful improvements in can perforating devices, and in particular, to a device for punching holes in the top of a can of that character 5 in which condensed milk is sold; the principal object of the invention being to provide a can perforating device that may be attached to a table or other support, and that can be formed completely out of one 10 sheet of metal by a single punching operation.

With the foregoing objects in view, my invention resides in the novel manner of forming the device and in the shaping of 15 parts thereof so that they will serve as a support for the can to be perforated and as a guard for sustaining the can in position when the punch pierces the hole in the upper end thereof.

20 In accomplishing these and other objects of the invention, I have provided the improved details of construction, the preferred forms of which are illustrated in the accompanying drawings wherein—

25 Figure 1 is a plan view of the punched out blank from which the device is formed.

Figure 2 is a perspective view of the device in operative position.

Referring more in detail to the drawings—

1 designates the flat blank of sheet metal from which the device, as shown in Figure 2, except the punch lever, is formed, the blank being formed as shown by a single 35 punching operation. The blank comprises a flat end portion 2, adapted to serve as the mounting base for the perforating device and which is almost separated from the other end portion 3 of the blank by slots 4—4 which lead into the blank from opposite side edges leaving only a narrow central neck portion 5 whereby the parts 2 and 3 are joined. The part 3 is adapted to serve as a positioning support or guard for the 40 can being perforated and also as a mounting for the punch or perforating lever 6 presently described.

Extending centrally from the upper end of the portion 3 of the blank are standards, 50 or extensions, 7—7, provided at their ends with aligned apertures 8 for receiving a screw, or bolt, 9 whereby the punch lever 6, as shown in Figure 2, is pivotally mounted.

55 The punch lever is formed from a single

piece of metal that may be stamped out of the metal sheet at the same operation when blank 1 is punched, and it comprises an outer end portion 10, and, on its under edge, has two downwardly projecting piercing points 60 11—11, adapted for piercing the end wall of a can adjacent its opposite edges.

A hole, 12, is provided centrally in the base 2 for receiving a screw, or other means for securing the device in place upon a table 65 or other form of support.

When the metal blank has been formed in the manner described, the upper portion 3 is bent at the neck portion 5 at a right angle to the base portion 2, as is illustrated in 70 Figure 2, and the opposite side portions of the part 3 are curved radially inwardly to form wing guards that receive the can therein; the radial curvature of the wings to be slightly greater than that of a condensed 75 milk can for which the device is intended. The extensions 7—7 that form the support 3 for the punch lever are bent inwardly in spaced-apart relation to receive one end of the lever 6 which is pivotally attached there- 80 to by the bolt 9, as above described.

In use, the can, as indicated at 15 in dotted lines in Figure 2, is placed upon the base 2 within the wing guards of the upright portion 3 which serves to retain the 85 can properly in position. The punch lever is then pressed down by the handle 10 and the points 11 caused to pierce the upper end of the can.

Having thus described my invention, what 90 I claim as new therein and desire to secure by Letters-Patent, is:

A device of the class described comprising a single metal piece that is bent at right angles forming a base and an upstanding 95 portion and having the side edges of the upstanding portion severed from the base and curved inwardly to partially encompass a can placed in the base, extensions formed on the upper end of said upstanding portion and bent in spaced apart, parallel relation, and a punch lever pivotally attached at one end between said flanges and provided with piercing points on its under edge adapted to pierce holes in the top of the can 100 when positioned upon said base.

Signed at Seattle, King County, Washington, this 14th day of January, 1926.

MYRON E. KENNEY.
